UNITED STATES PATENT OFFICE.

FREDERICK C. KROEGER, OF ANDERSON, INDIANA, ASSIGNOR, BY MESNE ASSIGNMENTS, TO DELCO-REMY CORPORATION, OF DAYTON, OHIO, A CORPORATION OF DELAWARE.

IGNITION TIMER.

Application filed November 6, 1922, Serial No. 599,238. Renewed February 3, 1927.

This invention relates to ignition apparatus for internal-combustion engines, and more particularly to the timer and distributor unit commonly called the distributor.

5 It is among the objects of the present invention to provide a distributor which is efficient and reliable and can be produced at a relatively low cost.

10 A further object is to produce a distributor which is readily adapted to receive any one of a set of interchangeable parts such as sets of timer cams, distributor rotors and distributor heads, whereby the distributor can be adapted for either direction of rotation of its driving shaft, and can be adapted to provide ignition for engines having different numbers of cylinders, for example, 4, 6 or 8 cylinders. In this manner the number of different parts required for producing 15 apparatus for different engine requirements will be reduced to the minimum.

20 A further object is to provide a distributor in which the internal electrical circuits are provided without the use of wire conductors.

25 A further object is to provide means for manually adjusting the distributor, said means cooperating with any one of a series of manual timing range stops each of which 30 permits the proper range of manual adjustment for the particular engine with which the distributor is to be used.

35 Further objects and advantages of the present invention will be apparent from the following description, reference being had to the accompanying drawings, where a preferred embodiment of the present invention is clearly shown.

In the drawings:

40 Fig. 1 is a side view of a distributor embodying the present invention;

45 Fig. 2 is a plan view thereof with the distributor cap and segment removed;

50 Fig. 3 is a plan view of a terminal bracket and contact support;

55 Fig. 4 is a side view thereof looking in the direction of the arrow 4 in Fig. 3;

60 Fig. 5 is a sectional view on the line 5—5 of Fig. 1;

65 Figs. 6, 7 and 8 are sectional views taken on the lines 6—6, 7—7, and 8—8, respectively of Fig. 2;

70 Fig. 9 is a side view of the distributor

looking in the direction of the arrow 9 in Fig. 1, certain parts being in section, the 55 sections being taken on the line 9—9 of Fig. 1;

75 Fig. 10 is a plan view showing the timer cup with the automatic advance mechanism positioned therein;

80 Fig. 11 is a longitudinal sectional view of a portion of the rotatable mechanism of the timer, the section of the automatic advance mechanism being taken on the line 11—11 of Fig. 10;

85 Fig. 12 is a plan view of the circuit breaker base;

90 Fig. 13 is a fragmentary sectional view of a portion of the circuit breaker base and a portion of the distributor head;

95 Fig. 14 is a plan view of the distributor segments adapted for counterclockwise rotation of the distributor driving shaft.

100 Fig. 15 is a plan view of an assembly of the rotating parts adapted for counterclockwise rotation;

105 Fig. 16 is a plan view of an assembly of the rotating parts adapted for clockwise rotation; and

110 Fig. 17 is a plan view of the distributor rotor shown in Fig. 16.

115 20 designates a timer cup which has a cylindrical shank 21 and an annular flange 22 concentric with said shank. Shank 21 is centrally apertured to receive a bushing 23 85

which provides a bearing for the main shaft 24. Shaft 24 carries at its lower end a coupling 25 having tongues 26 adapted to be engaged by notches in a similar member carried by another shaft not shown which 90

shall drive the shaft 24. Shaft 24 carries and drives a weight support or base 27 to which are attached weight studs 28 each serving as a pivot post for a weight lever 29

which is preferably formed by punching 95 from sheet material, and has welded thereto a weight plate 30. Each weight lever 29 is spaced from the weight base except where the weight lever rests upon one or two buttons 31 which are struck up from the upper surface of the weight base. This construction tends to reduce friction which

100 would retard the movement of a weight lever 29 about its pivot 28. Each weight is provided with a finger 32 which engages an 105

arm 33 of the automatic cam or spider 34.

Spider 34 is attached to the lower end of cam shaft 35 which is journaled upon the reduced upper end 36 of the driving shaft 24. (See Fig. 11). The lower end of shaft 35 is spaced from the shoulder 37 of the shaft 24 by means of a washer 38. Two spider arms 33 each carry a spring post 39, and the other arm 33 carries a spring post 39^a. Each spring post 39 or 39^a is connected by spring 40 with an adjacent weight post 28. The spring post 39^a is long enough to extend through a hole 27^a in the plate 27, while the other posts 39 do not extend to the plate 27. Obviously centrifugal force will cause the weights 29 and weight plates 30 welded thereto to swing out towards the periphery of the weight base 27 and will cause the automatic spider 34 to be rotated in a counterclockwise direction to advance the ignition timer as the speed increases as will be apparent more clearly hereinafter. The lower end of post 39^a extending into hole 27^a cooperates with plate 27 to provide a stop limiting the movement of the weights 29. In the innermost position of the weights 29 the springs 40 extend radially and the post 39^a practically touches one side of the hole 27^a. It is apparent that the governor is constructed for a timer in which the timer cam shaft is to revolve in a counterclockwise direction.

If it is desired to adapt the apparatus for an installation in which the timer shaft is revolved in a clockwise direction, the weights 29 are reversed upon their posts 28 as shown at 29^a in Fig. 16 and have the weight plates 30 welded on the opposite side from that shown in Fig. 10, whereby these weights with their plates are arranged for counterclockwise rotation outwardly upon their weight posts. Therefore in such a construction when the weights swing out the spider 34 will be rotated clockwise relative to the shaft 24, and will advance the timer cam shaft 35 in a clockwise direction as viewed in Fig. 16. It is also necessary to interchange the post 39^a with a post 39 so that the post 39^a in its new location will extend into a hole 27^b in plate 27. When the automatic mechanism is at rest, the post 39^a in Fig. 16 will practically touch one side of the hole 27^b. Therefore hole 27^b serves the same purpose as the hole 27^a does when the apparatus is arranged for counterclockwise rotation.

The timer cam shaft 35 is provided with a tapered portion 41 and a reduced upper end which is threaded at 42 to receive a nut 43. (See Fig. 11). The timer cam 44 is centrally apertured to receive the tapered portion 41 and the reduced portion 42, the cam having conical portions 45 and 46 which bear against the tapered conical portion 41 of the shaft 35. After the cam 44 has been located in proper position of adjustment upon the shaft 35, the nut 43 is tightened down to secure the cam in adjusted position. The cam 44 is provided with a hub 47 which is substantially cylindrical except where provided with the flat 48. (See Fig. 15). A distributor rotor 49 is formed preferably of bakelite or equivalent condensation product and is provided with a recess 50 adapted to receive the hub 47, said recess including a flat portion 51 conforming to the flat 48. This construction provides for locating the distributor rotor in proper relation to the cam 44. The rotor 49 supports a segment 52 which is riveted at 53 to a preferably metallic member 54, or insert around which the distributor rotor is molded. A felt wick or plug 35^a acts as a lubricant reservoir to supply lubrication between parts 35 and 36.

The cam 44 as shown in Fig. 2 will provide ignition for a six cylinder four stroke cycle engine. In order to accommodate the distributor to a four or eight cylinder engine, it will be necessary among other things to substitute for the cam 44 other cams having four or eight lobes, for example, to suit the requirements of a four or eight cylinder engine.

The flange 22 of timer cup 20 supports a circuit breaker base 60, said base being held down by screws 61. The base 60 is provided with metal bosses 62, 63, and 64 preferably in arcuate alignment with a central aperture 65 surrounded by a boss 66, and with two elongated openings 67 and 68 preferably the same distance from the hole 65 and concentric therewith. (See Fig. 12). The base 60 is provided with a counter-bored recess 69 in alignment with the elongated hole 67 and this recess is adapted to receive one of a set of interchangeable washers 70 having the same external diameter but varying in internal diameter for a purpose to be described.

The circuit breaker plate 71 is provided with a central aperture adapted to receive the boss 66 which serves as a bearing for the plate 71. In order to yieldingly maintain the plate 71 in engagement with the bosses 62, 63 and 64, and the base 60, the plate 71 is provided with hold-down studs 72 which extend from the plate 71 down through the arcuate slots 67 and 68, and each of these studs is reduced at its lower end to provide a threaded portion for engagement by a nut 73. The reducing of the lower end of the stud in diameter provides the stud with a stop shoulder 74 which definitely limits the distance to which the nut 73 can be screwed along the stud 72. Between the nut 73 and the underside of the base 60, the stud 72 is surrounded by a plain washer 75 and a spring washer 76. The plain washer 75 is yieldingly pressed by the spring washer 76 against the lower face of the circuit breaker.

- base, hence the circuit breaker plate 71 will be yieldingly held in position upon the bosses 62, 63, and 64 of the base 60. In this manner the plate 71 will be maintained substantially at right angles to the cam shaft and there will be little tendency for the plate to get loose and rattle. On the other hand this plate is relatively free to turn about the central boss 66.
- 10 A terminal bracket 80 is attached to the plate 71 but insulated therefrom, there being a non-conducting member 81 between the bracket 80 and the plate 71, and a non-conducting strip 82 is located on top of bracket 80 to receive the heads of rivets 83 the shanks of which are insulated from the bracket 80 by means of non-conducting washers 84 located within holes 85 and having sufficient internal diameter to receive the shanks of the rivets 83. Bracket 80 is provided with a condenser supporting ear 86 having a plain aperture 87 and with a contact supporting ear 88 having a threaded aperture 89. Bracket 80 is provided with a threaded aperture 90 for receiving the terminal screw 91, the lower end of which extends through an enlarged hole 92 provided in the handle portion 93 of the breaker plate 71. The handle 93 is provided with a hole 94 for receiving a link or the like by which the breaker plate 71 may be rotated from a distance as by means of the usual spark advance lever on the steering post of an automobile. It will be clear that when the circuit breaker plate 71 with all the parts mounted thereon as explained in detail in the following paragraph, is manually rotated about the boss 66 by the handle 93 the spark will be advanced or retarded according to the direction of rotation of said plate 71. The arcuate slots 67 and 68 in the base 60 through which the hold down studs 72 extend permits the rotation of plate 71 through a range depending on the length of said arcuate slots.
- 45 A set of interchangeable washers 70 (described above and clearly illustrated in Fig. 12) is provided for changing the length of the arcuate slot 67 and thus for providing the proper range of manual adjustment of the spark for the particular engine with which the distributor is to be used.
- The handle 93 of the breaker lever plate 71, the terminal bracket 80 and the non-conducting plate 81 extend through a notch 93^a in the flange or side wall 60^a of the base or container 60, the notch 93^a being slightly deeper than the combined thickness of these parts. The part 82 extends above the plane of the lower edge of the distributor head 150 which is seated upon the flange 60^a. The parts 71, 80, 81 and 82 have cylindrical edge surfaces indicated at 71^a, 80^a, 81^a and 82^a respectively in Figs. 5, 3 and 2. These cylindrical surfaces combine to provide a closure for the notch 93^a in all positions of the lever 93, and thus tend to prevent entrance of dust and other foreign matter within the timer housing provided by the base 60 and the head 150.
- 50 A threaded rod 100, carrying a nut 101 and a contact 102 and having a hexagonal head 103, has threaded engagement with the hole 89 in ear 88. By turning the hexagonal head 103, the rod 100 may be screwed in and out with respect to the ear 88 for purpose of adjustment and the rod 100 is secured in adjusted position by means of the lock nut 101. The contact 102 is adapted to be engaged by contact 104 riveted to an ear 105 substantially at right angles to the main portion of a breaker lever 106 which is located substantially parallel to the plate 71. The lever 106 is attached to a shaft 107 perpendicular to plate 71 having a portion which rests upon a circuit breaker lever bearing 108 carried by plate 71 and having a portion 109 which is journalled within the bearing 108. The lever 106 carries an intermediate portion which is bent down as indicated at 110 below the plane of the main portion of the lever and substantially perpendicular thereto and this portion 110 is bent substantially at right angles to the ear 105 as indicated at 111 and inwardly toward the timer cam 44. A cam rubbing block 112, preferably "micarta" specially treated, is attached by rivets 113 to the portion 111. The circuit breaker lever spring 115 is coiled around the parts 107 and 108 and has one end 116 pressing against the lever 106 and the other end 117 pressing against a spring retainer stud 118 which is carried by the plate 71. Stud 118 supports a condenser supporting arm 119 having a slotted hole 120 for receiving the threaded portion of a screw 121. Stud 118 also supports a circuit breaker lever retainer 122 which is held down by the screw 121 there being a lock washer 123 located between the head of screw 121 and the condenser support 119. The retainer 122 has its free end 123 dished out as shown in Fig. 6 to fit over the riveted end 124 of the hub 107 of the lever 106. By loosening screw 121 the retainer 122 may be swung to one side to permit removal of the breaker lever 106 from the base 71 for replacement or repairs.
- 55 The condenser designated as a whole by numeral 130 is one which is preferably in accordance with the invention disclosed in the copending application of August Toelle, Patent No. 1,599,853, issued September 14, 1926, and comprises a metal core 131 to which one foil of the condenser is grounded, this core 131 being tapped to receive a screw 132 and attached to but insulated from a condenser end cover 133 which is soldered to a metallic condenser can 134 which is spun over at 135 against a metallic button 136 which is electrically connected with the 125

other condenser foil. The button 136 carries a stud 137 having a threaded portion 138 passing through the condenser support 119 and receiving a lock washer 139 and a nut 140. The screw 132 passes through the hole 87 in the ear 86 of bracket 80 and attaches the condenser core 131 mechanically and electrically to the bracket ear 86. A lock washer 142 is located between the head of screw 132 and the ear 86 which is positioned against the protruding end of the core 131.

The distributor head 150 made of molded nonconducting material such as bakelite embodies certain features disclosed in the patent to O. F. Conklin No. 1,372,065, issued March 22, 1921. The head 150 is provided with a circular row of high tension cable receiving sleeves 151 disposed concentrically about a central cable receiving sleeve 152. Sleeves 151 are provided with metallic lining members 153 and needles 154 extend centrally of the lining members 153 and are attached to inserts 155, preferably of "Monel" metal which has been embedded in the bakelite of the head by molding the bakelite around the inserts. The cable receiving sleeve 152 is provided with a metallic lining 156 into which projects a needle 157 attached to a sleeve 158 within which slides a button 159 yieldingly maintained in engagement with the distributor segment 52 by means of a spring 160. The sleeve 152 receives the high tension cable from the secondary winding of the ignition coil, needle 157 enters in between the strands of the cable and provides a conducting path to the distributor segment 52 which distributes sparking impulses to the distributor posts or inserts 155 in recurrent sequence. Each of the needles 154 enters between the strands of a high tension cable received by the sleeve 151, said cable being attached to an engine spark plug. The distributor head 150 is held down upon the circuit breaker base 60 by means of spring clips 161 each having a hook portion 162 received by a recess 163 provided in the base 60. The flange 22 of the timer cup will close the lower end of this recess 163 when the base 60 is attached to the cup 22 as shown in Fig. 9 and therefore the hook end 162 will be retained within this recess. The clip 161 is provided with a loop 164 adjacent its upper end adapted to be received by a socket 165 provided by the head 150, and this loop 164 is adapted to snap over a shoulder 166 which prevents accidental displacement of the clip 161. The connection between the hook end 162 and the recess 163 is loose enough to permit swinging the clip 161 away from the head 150 so that the head can be removed from the base 60. The head 150 carries a lug 150^a adapted to fit between the sides 172 and 173 of a notch 174 for the purpose of locating the head on the base 60.

Lubrication for the shaft 24 is provided by means of a grease or oil cup 170 communicating through passage 171 with the shaft 24.

The ignition apparatus described is adapted for use in a grounded system of ignition in which the engine frame which supports the ignition timer serves as a part of the primary ignition circuit. In such systems it is customary to ground one terminal of the battery and to connect the other terminal with an ignition switch which in turn is connected with one primary terminal of the ignition coil. The other primary terminal of the coil is connected in any suitable manner with the terminal screw 91. The high tension terminal of the ignition coil is connected by a suitable cable with the sleeve 152 and needle 157 and the other distributor posts are connected by suitable cables with the spark plugs of the engine. There are no wire connectors located within the distributor. The terminal bracket 80 serves as a conductor to the stationary contact 102 and to one terminal of the condenser 130. The movable contact 104 is grounded through the breaker lever 106 and plate 71. The other terminal of the condenser 130 is grounded through its supporting member 119. The retainer 122 also serves to ground the breaker lever 106.

Where the timer cam normally rotates counter-clockwise as viewed in Fig. 2, the plate 71 will be rotated in a clockwise direction to advance ignition timing, but if the timer is to be used on an installation where the cam 44 will be rotated clockwise then the plate 71 will be rotated in a counter-clockwise direction to advance the ignition timing.

In order to arrange the distributor for clockwise rotation of the cam as viewed in Fig. 16, the cam 44 (shown in Fig. 15 showing the arrangement for counter-clockwise rotation) is relocated on the cam shaft 35. This new location of the cam relative to the automatic mechanism is indicated at 44^a. The same piece is used, therefore the flat will be in the position 48^a. The cams 44 and 44^a shown in Figs. 15 and 16, respectively are just touching the circuit breaker block 112. Further movement of cam 44 counterclockwise will cause the breaker contacts 102 and 104 to separate to cause sparking, and further movement of cam 44^a clockwise will cause the contacts 102 and 104 to separate.

It is apparent that automatic advance mechanism and the timer cam have been arranged for clockwise rotation without adding or substituting any new parts. The parts shown in Fig. 15 and preceding figures have been rearranged. In order to provide for distribution of the sparking impulses two rotors are used, rotor 49 (Fig. 14) for counterclockwise rotation and rotor 49^a (Fig. 130

17) for clockwise rotation (as viewed in Fig. 16). These rotors differ only in respect to the location of their flats 51 and 51^a, respectively, to their rotor segment 52. A normal line to the flat 51 (meaning a line passing through the axis of the rotor and perpendicular to the flat 51) is located below the center line of the rotor segment as viewed in Fig. 15. A normal line to the flat 51^a is located above the center line of the rotor segment as viewed in Fig. 16. The angle between the normal to the flat of the locating recess in the rotor and the center line of the rotor segment will be substantially one half the angular distance through which the cam is adjusted when changing over from one direction of rotation to the opposite. For example, if the cam 44 is rotated 40 degrees to bring it from the position shown in Fig. 15 to position 44^a in Fig. 16, then the angle between the normal to the locating flat in the rotor recess to the center line of the rotor segment will be 20 degrees.

To accommodate the distributors in engines having a number of cylinders other than six, it is obvious that the distributor head and the timer cam must be replaced by corresponding parts which are constructed to meet the particular ignition requirements. In other words, if the distributor is to be adapted for a four cylinder engine, the cam 24 must be replaced by a four lobe cam and the distributor head replaced by one having four instead of six equidistant sleeves 151 and posts 155.

While the form of mechanism herein shown and described constitutes a preferred form of embodiment of the invention, it is to be understood that other forms might be adopted, all coming within the scope of the claims which follow.

What I claim is as follows:—

1. In an ignition distributor, the combination with timer contacts; of a cam for separating the contacts; a cam supporting shaft having a lever arm; a drive shaft; and speed responsive means for angularly adjusting the relation of said shafts including a weight support, a pivot post carried by said support, and a weight member including a weight lever having a finger, the lever being rotatably mountable on the post with either face of the lever adjacent the weight support whereby the finger may engage either side edge of the arm to permit either direction of rotation of the cam with respect to the drive shaft as the speed increases, said weight member including a weight plate attached to the lever on the side thereof remote from the support, whereby with the same set of parts the speed responsive means can be constructed to function for either direction of rotation of the drive shaft.
2. In an ignition distributor, the combination with timer contacts; of a cam for separating the contacts; at least two arms attached to said cam and extending transversely therefrom; a drive shaft; and speed responsive means for actuating said arms for angularly adjusting the relation of the cam to the drive shaft including a weight support attached to said shaft, weight members pivotally mounted on said support and each having a finger engaging one of the cam arms to angularly adjust said cam from a normal position, spring means for returning the arms to normal position, and a pin insertable through a hole in either cam arm and extending into either of two holes in the weight support provided, respectively, immediately under the holes in the cam arms, the holes in the weight support being larger than the pin and so disposed that when the pin is inserted through one cam arm into a weight support hole said pin cooperates with the weight support to provide a stop limiting the movement of the cam arms in one direction from normal, and when the pin is inserted through the other cam arm into the other weight support hole the pin cooperates with the weight support to limit the movement of the cam arms in the opposite direction from normal with respect to the drive shaft.
3. In an ignition distributor, the combination with timer contacts; of a cam for separating the contacts; a stop pin; provisions for attaching the pin to the cam in two positions relative to the cam; a drive shaft; means for connecting the shaft with cam and for angularly adjusting the cam from a normal position with respect to the shaft in response to increase in speed; spring means for returning the cam to normal position; and a member connected to the drive shaft and provided with spaced apertures each for receiving the stop pin in one of its positions of attachment to the cam, said apertures being larger than the pin and so disposed that when the pin is in one of its positions of attachment to the cam and extends into one aperture said pin cooperates with the apertured member to provide a stop limiting the movement of the cam in one direction from normal, and when the pin is in the other position of attachment to the cam and extends into the other aperture said pin cooperates with the apertured member to provide a stop limiting the movement of the cam in the opposite direction from normal with respect to the drive shaft.
4. In an ignition distributor, the combination with a support having a recess; of a breaker plate rotatable on said support; a stationary contact carried by said plate; a breaker lever having a movable contact carried on said plate; a cam for actuating the lever; a stop pin attached to the plate; said recess in the support adapted to receive and retain in fixed position any one of a set of

rating the contacts; a stop pin; provisions for attaching the pin to the cam in two positions relative to the cam; a drive shaft; means for connecting the shaft with cam and for angularly adjusting the cam from a normal position with respect to the shaft in response to increase in speed; spring means for returning the cam to normal position; and a member connected to the drive shaft and provided with spaced apertures each for receiving the stop pin in one of its positions of attachment to the cam, said apertures being larger than the pin and so disposed that when the pin is in one of its positions of attachment to the cam and extends into one aperture said pin cooperates with the apertured member to provide a stop limiting the movement of the cam in one direction from normal, and when the pin is in the other position of attachment to the cam and extends into the other aperture said pin cooperates with the apertured member to provide a stop limiting the movement of the cam in the opposite direction from normal with respect to the drive shaft.

5. In an ignition distributor, the combination with timer contacts; of a cam for separating the contacts; a stop pin; provisions for attaching the pin to the cam in two positions relative to the cam; a drive shaft; means for connecting the shaft with cam and for angularly adjusting the cam from a normal position with respect to the shaft in response to increase in speed; spring means for returning the cam to normal position; and a member connected to the drive shaft and provided with spaced apertures each for receiving the stop pin in one of its positions of attachment to the cam, said apertures being larger than the pin and so disposed that when the pin is in one of its positions of attachment to the cam and extends into one aperture said pin cooperates with the apertured member to provide a stop limiting the movement of the cam in one direction from normal, and when the pin is in the other position of attachment to the cam and extends into the other aperture said pin cooperates with the apertured member to provide a stop limiting the movement of the cam in the opposite direction from normal with respect to the drive shaft.

6. In an ignition distributor, the combination with a support having a recess; of a breaker plate rotatable on said support; a stationary contact carried by said plate; a breaker lever having a movable contact carried on said plate; a cam for actuating the lever; a stop pin attached to the plate; said recess in the support adapted to receive and retain in fixed position any one of a set of

apertured members for permitting the projection thereinto of said stop pin, the external dimensions of said members being the same but the apertures varying in size to 5 provide for varying ranges of movement of said stop pin.

5. An ignition device comprising in combination, co-operating contacts; a plate carrying one of said contacts; a pivoted lever 10 carrying the other contact; a condenser having terminals extending therefrom; and means for supporting said condenser and electrically connecting it between the two contacts, said means including an apertured 15 ear supported by the plate for receiving one terminal of the condenser, and an apertured arm for receiving the other condenser terminal, said arm being adjustably connected with the pivoted lever.
- 20 6. An ignition timer comprising in combination, a base; a breaker lever support on said base; a cover on said breaker lever support; and spring clips hingedly retained between the base and the said support, and 25 including hook portions adapted to engage the cover.

7. An ignition timer comprising in combination, a base; a breaker lever support carried by said base; a cover for said support; 30 and spring clips hingedly retained between the base and said support and including hook portions adapted to engage the cover, said clips and support having co-operating provisions whereby the clips may have a limited 35 swinging movement, but are maintained in attachment to the said support and base while said support is attached to the said base.

8. An ignition timer comprising in combination, a base; a plate carrying the distributor timer mechanism secured to said base and including recesses in the edge engaging said base, said recesses having enlarged inner portions; a distributor head on 40 said plate; and spring clips adapted to be inserted in the recesses before the plate is secured to the base, said clips having provisions extending into the enlarged portions of the recess whereby the clips are hingedly 45 retained between the base and plate when the plate is secured to the base, and hook formations on the clips for securing the distributor head to the plate.

9. An ignition device comprising in combination, a cup-shaped container having a 50 notch in its flange; a breaker plate rotatably supported in said container and having a handle portion extending through the notch; a breaker lever having a contact and pivotally supported on the breaker plate; a terminal bracket insulatingly carried by the 55 breaker plate and having a contact supported thereon for engagement by the breaker lever contact, and a portion aligned with, and 60 extending through the notch with the han-

dle portion of the breaker plate; and a connector carried by the terminal bracket outside the container.

10. An ignition device comprising in combination, a cup-shaped container having a 70 notch in its side wall; a breaker plate rotatably supported in said container; a handle extending from the breaker plate through said notch; a condenser; a breaker lever pivotally supported on the breaker plate; a terminal bracket insulatingly mounted on said plate and having a portion extending along said handle through the notch; and two angular portions, one of which supports a contact adapted to be engaged by the breaker 80 lever, the other supporting one end of the condenser; and a terminal carried by the terminal bracket outside the container. 75

11. An ignition device comprising in combination, a housing; a base plate rotatably supported in said housing; an interrupter mechanism in said housing, including a stationary contact supported by a terminal plate insulatingly carried on the base plate, and a movable contact carried on a breaker lever; 90 a post on the base plate pivotally supporting a breaker lever; a stud on said base plate adjacent the said post; a clip adjustably secured on the stud by means of a screw, and adapted to have one end rest 95 on the breaker lever to hold it in position on the post; a conductor arm having one end adjustably secured to the stud by the screw holding the clip, said arm having an aperture in its free end; and a condenser, supported between the said conductor 100 arm and terminal plate.

12. An ignition device comprising in combination, a cup-shaped container having a notch in its side wall; a cover seated upon the said side wall; a breaker plate rotatably supported within the container and having an operating handle extending through said notch; a terminal bracket within said container and having a portion extending 105 through the notch and superposed upon the handle; a non-conducting plate located between the bracket and breaker plate, said breaker plate, terminal and bracket and insulating plate having cylindrical edge portions cooperating to provide a closure for the notch in all operating positions of the handle; and a circuit make and break device, supported by the breaker plate and electrically connected with the terminal 110 bracket. 115

13. An ignition device comprising in combination, a cup-shaped container having a notch in its side wall; a breaker plate rotatably supported in the casing and coaxially thereof, said plate having a gate portion adjacent the notch extending beyond each end of said notch, said gate portion being provided with an outer, arcuate edge concentric to and coinciding with the inner 120 125 edge.

surface of the casing and adapted to move in close proximity thereto; an arm extending from the breaker plate through the notch providing an operating lever therefor; an insulating plate on the gate portion of the breaker plate; a terminal bracket on the insulating plate, having the same contour as the gate portion mentioned, and having a portion extending through the notch in su-
10 perposed alignment with the operating lever; a terminal on said bracket outside the casing; means insulated from the breaker plate and terminal bracket for holding them together with their interposed insulating plate; and a breaker mechanism supported on the breaker plate and terminal bracket.

In testimony whereof I hereto affix my signature.

FREDERICK C. KROEGER.
